A. Hurd.

Pouncing Hats.

N° 16588

Patented Feb. 10, 1857.

UNITED STATES PATENT OFFICE.

ALVIN HURD, OF DANBURY, CONNECTICUT.

METHOD OF SURFACING FELT HATS.

Specification of Letters Patent No. 16,588, dated February 10, 1857.

To all whom it may concern:

Be it known that I, ALVIN HURD, of Danbury, Fairfield county, and State of Connecticut, have invented a new and Improved 5 Method of Surfacing Felt Hats, of which the following is a clear and exact description, reference being had to the annexed drawings, making part of this specification.

Figure 1 is a perspective view of Fig. 2, a 10 section of the bench and crown block. Fig. 3, a section of the top block. Fig. 4, a view of the stone; details of which will be referred to hereafter.

In manufacturing the hat, the effort of 15 the trade has been to produce a fine, even, and velvet-like surface upon the hat, and by some easy and sure process. The importance of such a result has brought out several plans, and elicited much effort of the 20 trade. But no one has arrived at a satisfactory result until my discovery.

The process usually adopted is to rub the 25 hat wet or dry with a pumice or fine grit stone until the coarse surface is removed, but the result has ever been to produce a spotted surface, in consequence of the unevenness of the felt, and the want of something to regulate and assist the action of the stone. My plan has reduced the process to a sure 30 and satisfactory result, producing uniform work.

The explanations of the drawings are, Figure 1, *a*, bench; *b*, elastic cover; *c*, block to surface the side crown upon; *d*, block to 35 surface the tip upon; *F*, the hat placed upon the elastic cover showing the application of the stone *E*; the box that contains the pulverized pumice is shown at *j*.

Fig. 2, is a vertical section of the bench *a* 40 and crown block *c*; the elastic cover *b*, and hat *F*, is shown with the position of the

stone *E*, while surfacing the side crown. The elastic cover *b* upon the bench *a*, is shown, and the pin *G* upon which the black revolves.

Fig. 3, is a vertical section of the tip block *D*, showing the elastic cover *b*. Fig. 4, a view of the stone *E*.

It is well known to the trade that felt hats are not of uniform thickness, consequently when pounced some parts will be affected more than others, producing a motley surface, which destroys the beauty of the hat. To overcome the above difficulty we place the hat (after it is ready to finish) 55 upon the block *c*, to surface the side crown. We then sprinkle upon the hat pulverized pumice, then rub up and down the crown with the stone *E*, reaching from a little above the square to below the band. From 60 this block we remove the hat to the tip block *d*, where the tip is surfaced in like manner as the side crown. The brim is surfaced upon the bench *a*, as shown in Fig. 1. The thicker parts settle into the elastic 65 cover, presenting thereby an even surface to the action of the stone. The powdered pumice serves to prevent the stone from cutting too deep, also in connection with the stone to cut off the fur evenly. Sometimes we double the hat, the under half acting as the 70 elastic cover.

What I claim as new and my invention in the above described process, is—

Surfacing the hat upon the elastic cover 75 or bed for the purpose and in the manner substantially as herein described.

ALVIN HURD.
